United States Patent

Des. 234,277
Patented Feb. 11, 1975

234,277

STOOL

Philip Robert Salmon, 1416 S. Sheridan Way, Sheridan School of Design, Mississauga, Ontario, Canada, and Hugh Campbell Hamilton, 4 Hedgewood Road, Willowdale, Ontario, Canada

Filed Apr. 23, 1973, Ser. No. 353,601

Term of patent 14 years

Int. Cl. D6—01
U.S. Cl. D6—26

FIG. 1

FIG. 2

FIG. 3

FIG. 4

FIG. 1 is a perspective view of a stool embodying our new design;

FIG. 2 is a plan view from the top of the stool illustrated in FIG. 1;

FIG. 3 is one side view of the stool illustrated in FIG. 1; and

FIG. 4 is a side view of the stool illustrated in FIG. 1 from the opposite side to that illustrated in FIG. 3.

We claim:

The ornamental design for a stool, substantially as shown.
